Application May 13, 1939, Serial No. 273,400

9 Claims. (Cl. 29—84)

Our invention relates to a machine to facilitate the assembling of the conventional pocket knife. These knives may be of the folding type with blades at both ends, or only at one end, in which there are tensioning springs the length of the handle for holding the blades in place when open or closed. The machine is so arranged that an operator can assemble the various parts quickly and easily to meet the needs of modern production methods. In general, the machine provides a rest for the parts of the knife during assembly in such a manner that the component parts are placed upon assembly pins which serve to position the several parts together before fastening. These pins, which are part of the machine, are spring-pressed and the permanent rivets can be inserted in the holes occupied by these pins by means of a lever and suitable guides holding the rivet pins, the rivet pin forcing the spring-pressed pin out of its hole in the knife elements as the rivet pin is forced into place in said hole.

It is to be understood, however, that any other type of fastening means can be inserted by the machine, such as a screw, for example.

As the spring element in the conventional pocket knife is under tension, it is clear that it must be forced into place so that the final rivet can be put in to hold the knife in assembled relation and that such is difficult with so many parts to be held. The invention described herein shows one means of doing this wherein a suitable finger applies the proper pressure to the spring, thus aligning the rivet holes to allow the final rivet pin to be put into position easily.

There has also been provided a safety guard with a transparent face for the machine. This safety guard is so arranged that it is lifted out of place while the parts are being positioned in the machine by hand, and covers these parts as the press pushes the rivet pins into place. The guard prevents injury to the worker from flying pieces and also prevents operation of the press if the guard is not entirely in its safe position, thereby protecting the hands of the person assembling the knife.

It can readily be seen that it is difficult to assemble such a knife with this type of spring, which requires considerable force to put it into position so that the rivets can be driven through, particularly when there are numerous pieces to be held in place. From the following description, in which is disclosed one embodiment of the invention and the details thereof, it will be apparent to those skilled in the art to which this invention

most nearly pertains, how the foregoing objects are accomplished.

In the drawings:

Fig. 1 is a plan view of one form of the apparatus for carrying out the invention.

Fig. 2 is a side elevation, with some of the parts in section (looking toward the right side of the operator of the apparatus of Fig. 1).

Fig. 3 is a perspective view of the assembling 10 jigs (looking in the same direction as Fig. 2).

Fig. 4 is a secondary elevation view taken on the line IV—IV of Fig. 2 which clearly shows the aligning pins.

Fig. 5 is a perspective view of an outside scale 15 of a knife with the handle and bolsters assembled thereto.

Fig. 5a is a perspective view of one of the knife 20 springs with a fragmentary view of one of the blades held in its relative position with respect to the spring.

Fig. 5b is a perspective view of a middle scale of a knife.

Fig. 5c is similar to Fig. 5a.

Fig. 5d is similar to Fig. 5.

Fig. 5e is a perspective view of one of the rivet 25 pins to be used in assembling the parts shown in Figs. 5 to 5d inclusive.

Fig. 6 is a simplified view of the pin driving lever and safety guard lever showing them in raised 30 position.

Similar characters refer to similar parts throughout the drawings.

In general the machine comprises a frame 35 which supports the various parts of the device and which is in turn supported on a table of suitable height. Referring to Fig. 2 of the drawings, a table top 10 supports the frame 20 which is secured tightly thereto by bolts 11' and 12. A pin driving lever 101 (Figs. 1 and 2) has bosses 40 102 through which a fulcrum shaft 103 extends. This shaft is journaled in ears 104 which extend upwardly from the base portion 210 of the frame. The table is cut away to permit a downwardly extending portion 105 of the pin driving lever to 45 extend below the table top where it is secured by appropriate bolts 106 and 107 to a foot operated lever 108 and a counterweight 109. In the interest of brevity the foot lever and counterweight are not shown. The counterweight generally comprises a cylindrical mass of metal having an extending arm which, as shown in the drawings, is bolted to part 105. The foot lever is merely a bar, usually of wrought iron, drilled to receive the securing bolts 106 and 107 at the top and having a laterally extended foot rest or

receiving piece at or near its bottom (not shown). The pin driving lever 101 has a forwardly extending portion 110 upon which there is a boss 111 in which is anchored a laterally extending pin 112. This boss and pin are a portion of a safety arrangement which will be discussed later. The pin driving lever is shaped at its forward extremity so that it may receive various tools or jigs carrying driving pins, it being understood that the type of jig or tool depends upon the type of knife being assembled, the chief variation being in the location of the driving pins in the same.

The forward portion of the frame is also arranged as shown at 211 (Fig. 2) to receive various fixtures or jigs, depending upon the type of knife being assembled. The frame has bosses 212 and 213 (Fig. 1) in which is journaled an eccentric carrying shaft 214. A hub 215 secured to one end of this shaft and a collar 216 carrying a set screw 217 maintain this shaft in position. The hub 215 is secured to the said shaft by a pin 218, and is drilled to receive an operating lever 219. As will be clear from Fig. 3, there is a projecting pin 221 in the collar 216. This pin cooperates with a pin 220 in the frame 20 to limit the rotation of the shaft 214. It is evident that the operating lever could also be mounted on the other side of the machine by a mere reversal of the position of the related parts just described.

A bell crank lever 301 (Figs. 1, 2 and 3) is pivotably mounted on the forward portion of the frame 20 by means of a shaft 302 which operates as a stub shaft extending through a boss on the said lever and an ear 222 on the frame. A nut 303 cooperates with the head 304 on the shaft 302 to secure the parts in proper position and relation. One arm of the bell crank lever 301 extends back under the frame as shown at 305, and is apertured at 306 to receive one end of a spring 307, which spring, having its other end anchored to the frame by means of a web 308 between apertures 309 and 310, serves to maintain the lever in what, for convenience, may be called its retracted position. The upper surface 311 of this portion of the lever is in contact with an eccentric 312 mounted on the shaft 214. The eccentric has a flat side 313 which permits a faster and further movement of the lever, which will be explained hereinafter.

The tool block 314 is carried on the upper surface of the vertical arm of bell crank lever 301 by means of bolt 316 entering a threaded hole in said vertical arm. The enlarged hole in the tool block for bolt 316 allows adjustment of the block by set screw 317. The tool block has an upper surface 318 engaging guide holder 407 at 417 to hold the same in place when the guide holder 407 is in its position shown in Fig. 2. The tool block has projecting pieces 315 thereon for entering the opening in the knife or the outside of the spring to engage the spring to bring the holes in alignment so that the pin can be inserted. The shape and number of these projections are varied in accordance with the knife to be assembled as will be described in more detail later.

Referring now to Fig. 3, it will be seen that the frame 20 carries a die bed 401 having upright ears 402 and 403. These ears are threaded to receive taper point pivoting screws indicated at 403 and 404 in Fig. 1. These screws carry locknuts 405 and 406, respectively. They maintain the guide holder 407 in a pivoting arrange-

ment. The guide holder is most clearly shown in Fig. 3, but the manner in which it is secured to the ears on the die bed is more clearly shown in Fig. 1, in which the points 408 and 458 are shown as extending into the drilled portions 409 and 410 of the guide holder. Secured to the bottom of the die bed is a channel-shaped member 411 which carries a plurality of aligning pins, 451, 452, 453 (Fig. 4). These aligning pins are surrounded by springs 413 which in a normal position cause the pin to extend through apertures 414 in the die bed. The springs acting on shoulders 413' urge the pins upwardly.

Attention is now directed to Fig. 4, where a locating stop 415 is secured to the die bed 401 by means of a bolt 416. Although Fig. 4 shows three aligning pins 451, 452, 453, it is to be understood that these are not all used at one time. If a knife having blades on both ends is being assembled, then the central aligning pin is removed or fixed in retracted and inoperative position. If the knife is one having blades only on one end such as that resulting from assembling the parts shown in Fig. 5, one of the end aligning pins is kept retracted.

Assuming that the parts shown in Fig. 5 are to be assembled to produce a complete knife, aligning pin 453 in Fig. 4 will be removed or retracted. One side of the knife, for example

30 501, is placed on the die bed with the aligning pin points 451 and 452 extending through the holes 551 and 552. It will be understood that the exterior of the side of the knife is in contact with the die bed plate. The locating stop 415 assists the operator in locating and maintaining the knife side in its proper position. The guide holder 407 has been laid back or pivotably rotated on the points 408 and 458 back from the position shown in Figs. 2, 3 and 4. With the part 501 located on the pin points 451 and 452, a spring 511 is laid on top of the side 501 with the point 451 extending through the aperture 561. In the assembly of this type of knife, for example, with blades at one end only, the cutting edges of the blades are placed toward the left in Fig. 2 and the outside of the spring or closed side of the knife is toward the right for reasons that will appear presently. A blade 512 is either simultaneously or later placed in a position to co-act with the spring 511 by having its pivoting aperture 562 placed about the point 452. There is a tendency for a blade after being placed in such position to tilt or fall out of position because its only point of securement is at one end of the aperture 562. To avoid this and to free the hands of the operator for other matters, a plate 31 (Figs. 3 and 4) is secured to one side of the die bed. The extending portion of the blade lies on the plate and as a result, has no tendency to fall off of the pin point 452. The plate 31 is secured to the frame 20 in any manner desired, as for example, by screws, bolts, or welding. With the spring 511 and blade 512 in assembled position, an operator now places a dividing piece, or what is commonly known in the art as a scale 521, over them on the aligning pin points. Holes 571 and 572 receive the aligning pin points 451 and 452, respectively. A second spring 531 and blade 532 are now placed over the aforementioned scale and aligning pin point 451 extending through the aperture 581 and the aligning point 452 extending through the aperture 582. The other side of the knife 541 is now positioned over the other parts. It has drilled holes 591 and 592

which receive the aligning pin points 451 and 452, respectively. It can be seen that with the springs aligned on a common pivot or pin at the center, and the blades tending to push the end of the spring adjacent thereto outward, that the holes at the other ends of the springs will not be aligned with the other holes of the knife parts nor with the plunger 415. These ends of the spring will be to the left (Fig. 2) of the holes in the remaining parts of the knife through which a rivet passes in the finally assembled knife. In the knife illustrated, the sides or covers 501 and 541 have the usual bolstering end portions 502, 503, 504 and 505, inside of which are inlay sections 506 and 507 which may be of wood, bone, plastic or the like.

With all of the parts mounted on the aligning pin points 451 and 452, the guide holder 407 is pulled forward so that it overlies the stack of knife parts. This is the position which it occupies in Figs. 2, 3 and 4. A movement of the lever 219 (Figs. 1 and 2) causes the eccentric 312 (Fig. 1) to force the rearwardly projecting portion of the lever 301 downwardly. As a result the tool head 314 moves to the right in Fig. 2, and a projecting portion 318 contacts recessed portion 417, thereby pressing the stack of knife parts more closely together and more or less locking them in such a position. The three upwardly extending cylindrical portions 418, 419 and 420 are hollow and in alignment with the points on the aligning pins. In the assembly being described, the aligning pin points 451 and 452 extend into drilled holes which extend through portions 419 and 420 of the guide holder. The operator places rivet pins 11 in the proper guide holes 418-420, which in the case of the single ended knife being described will be in guides 419 and 420. At this stage the operator pushes backwardly on the foot rest portion of the lever 109. By reason of this lever pivoting on the shaft 103, the driving head moves downwardly and the pins 113, 114 and 115 enter the guides 420, 419 and 418 respectively (Fig. 4). A pin 114 extends into the guide 419, contacting the rivet pin 11. Continued downward movement of the head of the pin driving lever forces any knife rivet pins such as 11 in the guides into contact with the aligning pin points such as 451, and still further movement forces the knife pins through the knife assembly (in the place of the aligning pin points such as 451). The fit of the knife pins is very tight, so that the aligning pin springs 413 are not able to force the aligning pins upwardly again so long as the knife remains in its position in the assembling tools.

Reference to Fig. 5 and the preceding portion of the specification will make it clear that as yet there is no knife pin extending through apertures 563, 563, 573, 583 and 593. As explained previously, the reason for this is that the springs 511 and 531 are shaped so that their apertures 563 and 583 do not, in the absence of strain, register with the apertures 563, 573 and 593. No spring action would be exercised if they were shaped to fit in the knife assembly in the same way as scale 521.

It is also evident that the knife pins may be driven into place with the guide holder 407 merely lying on top of the knife parts before the lever 219 has been operated to clamp the parts in place, said lever 219 being operated to clamp the knife parts after the first set of pins have been put into position. A projection 223 may also be placed on arm 101, such that it will contact plate

5 407 and hold the knife parts firmly together as the pins are being driven, the lever 219 then being operated to clamp the plate 407 against the knife parts before pressure on the foot lever is released to allow 101 to move upwardly.

Having secured the knife parts by means of pins extending through the apertures 551, 561, 571, 581 and 591, 552, 562, 572, 582 and 592, respectively, the operator now releases the pressure on the foot receiving portion of the pin driving lever 101, with the result that the counter-weight 109 raises the lever out of pin driving position. When the upstanding arm of bell crank lever 301 moves to the right (Fig. 2) clamping 10 the guide holder on top of the stack of knife parts, another action takes place. The projecting pieces 315 on the block 314, being appropriately positioned, move forward into the spaces on opposite sides of the scale 521. Their shape and 15 size is such that they contact the springs 511 and 531 (at the right end in Fig. 5), placing them under stress and moving the springs outwardly in the knife frame. This follows since these 20 springs were already pivoted at 561 and 581, respectively, and could only pivot a short distance because position of the knife blades 512 and 532 was fixed by the apertures 562 and 582, and said blades restrained movement of the opposite ends of the springs. The action of the projecting 25 pieces 315, in straining the springs out of normal, causes the apertures 563 and 583 to become aligned with the apertures 553, 573 and 593. The operator now places a rivet pin in the guide 418, and by another foot movement of the lever 109, 30 101 causes the rivet pin to be driven through the knife parts. Thereafter, by relieving the foot pressure, lever 101 moves out of position, and by moving the lever 219 in the direction opposite from that previously described the arm 301 moves 35 318 toward the operator (or to the left in Fig. 2), releasing the guide holder 407. The guide holder is then lifted, being pivoted on the points 408 and 458, out of position, and the assembled knife lifted from the die bed. This last action removes 40 the pressure on the springs 413, and as a result the pins 451 and 452 are moved upwardly, thereby placing the aligning pin points of 451 and 452 in position to receive the parts of another knife. It will be understood that the rivet pins, such as 45, 11, project from opposite sides of the assembled knife, and that the excess pin material is removed by suitable cutting and swaging operation which smooths the end of the pin so that its surface is continuous with that of the bolster 50 through which it projects.

In a manner similar to this, if the knife is of the variety having blades at each end, the two outer pins 452 and 453 are used, the knife blade edges in this case facing to the right in Fig. 2 and the outside of the spring to the left. In this instance the shape of the springs is such that the holes for the pin in the middle lie farther from the center of the knife than the central aligned holes of the other parts of the knife. The projecting pieces 315 are then so designed as to push against the outside faces of the springs, thereby forcing them in, so that the middle rivet pin can be placed into position. It can be seen that the outer ends of the springs will then be forced against the knife blades. The component parts of the knife are laid in place, including the springs. It will be noted that the spring in this type of knife has only a hole in the center, and therefore when the first rivet pins at each end 55 are put in place, they do not go through the

springs. The springs must, however, be in their respective positions and are fastened in place by the final rivet pin as described.

The provision of safety means on the device is in accord with present factory practice to protect the worker, and a suitable device of this character is shown in the drawings. In Fig. 2 there is shown a safety shield 601 of transparent material, for example, Celluloid, cellulose acetate, polymerized methyl methacrylate or other plastic or plastic material. This transparent shield enables the operator to observe the action of the assembling device and at the same time protects the said operator from flying particles. The operator's hands are also protected as it is necessary that his hands be away from the pin operating lever as its stroke nears completion, because the presence of a foreign object will prevent the safety shield from completely shielding the work, as will appear presently. The shield is secured by suitable screws to arms 602 and 603 which, together with the shield, form a device somewhat resembling a horseshoe in shape. The free ends of this U-shaped device are suitably secured to brackets on the frame near the back of the same. In Fig. 1 screws 604 and 605 are shown as extending through the parts 602 and 603 into suitable brackets. One of these brackets is shown more in detail in Figs. 2 and 6, where it is indicated by the numeral 606. Bolts 607 secure this bracket to the frame. An irregularly shaped piece 608 is secured to the arm 602 on this side of the apparatus by means of screws 609, and this piece serves as an extension of the arm 602 to contain the hole through which the bolt shaft 604 extends into the bracket. A pin 610 (Figs. 1 and 6) extends inwardly from the piece 608 over the edge of the pin driving lever 101. Movement of the pin driving lever upwardly causes it to contact this pin and raise the safety shield 601 from its protecting position. Downward movement of the pin driving lever does not carry the safety shield with it because there is no positive connection between the two. Ordinarily the safety shield and its supporting arms fall to protecting position of their own weight when the pin 610 is released by the downward movement of the pin driving lever 101. Downward movement of the safety shield causes the portion 611 to move so that when the shield is all the way down, the pin 112 on the pin driving lever 101 can pass by it as the lever 101 is operated. If this action does not take place, the pin 112 contacts the part 608 and its further movement is blocked, thereby preventing operation of the pin driving lever unless the safety shield is in position.

In Fig. 6 can be seen the relation of these parts when the pin driving lever 101 is raised, contacting pin 610 and raising the safety shield. As is shown, the centers of 604 and 103 are different so that pin 112 now overlies 608 and it is necessary for the safety shield, carried on 603, to be substantially fully in protecting position in order for pin 112 to pass by 608. If such is not the case, pin 112 will engage 608 and be prevented from going down. Thus it can be seen that the operator's hands must be away from the pin driving lever as it comes down, or that the safety shield be completely in operative position so that the safety shield is in safety position before the pin driving lever can complete its stroke.

As previously indicated, there is an eccentric 312 on the shaft 214. Rotation of the shaft 214 by means of the lever 219 causes the inwardly projecting end of the lever 301 to be lowered or to

allow it to be raised (by means of the spring 307), as the case may be. In order that the tool head 314 on the other end of the lever 301 may be brought into operative position and released

5 therefrom more rapidly than would be the case with a conventional eccentric, one side of the eccentric shown has been flattened as indicated at 313. This permits an acceleration of movement during the last part of the travel indicated as the 10 tool head is being moved into inoperative position.

It is to be understood that the particular arrangement of the die head and the spring tensioning projecting pieces or other means to put pressure on the spring is not limited to the disclosure herein, which is merely an example of the invention as applied to the knife of the configuration shown. The die head and related parts can be made of any desired shape to fit the knife to be assembled as can also the tool head. The 15 positioning member and location and number of the rivet pins control the corresponding dies and design of the machine, and is not limited to that shown. A knife with any number of rivet pins can be assembled by the method disclosed, 20 as the machine can have as many pins and guides as desired. It is also clear that a knife with one or more layers of blades can be assembled on a machine of the type described.

The invention is not limited to the details 30 shown herein, described in the drawings and illustrated, but is to be construed as covering all equivalent devices falling within the scope of the appended claims.

What is claimed is:

35 1. In a machine for assembling pocket knives comprising a spring and other parts to be assembled, the combination of a frame, a die bed fixed to said frame and having at least two locating pins upon which to assemble the unstressed spring and other parts, means pivotally mounted on said die bed for inserting permanent pins in place of the said locating pins, means pivotally mounted on said frame and movable transversely to said die bed to stress the knife 40 spring, and means pivotally mounted on said frame and movable substantially vertically relative to said pin inserting means and said die bed to insert a final permanent pin while the spring is so stressed.

45 2. In a machine for assembling pocket knives comprising a spring and other parts to be assembled, the combination of a frame, a die bed fixed to said frame and having at least two locating pins for holding the parts and the unstressed spring in place, means to hold the parts so assembled in place, said holding means including guide means to insert permanent pins in place of said locating pins, means pivotally mounted on said frame and movable transversely to said die bed to stress the spring, and means pivotally mounted on said frame and movable substantially vertically relative to said holding means and said die bed to insert a final permanent pin while the spring is so stressed.

50 3. In a machine for assembling pocket knives comprising a spring and other parts to be assembled, the combination of a frame, an apertured die bed fixed to said frame having at least two retractable pins in said apertures for guiding the assembly of the unstressed spring and the other parts, means pivotally mounted on said apertured die bed for inserting permanent pins in place of the retractable pins, means pivotally mounted on said frame and movable transversely to said die bed to stress the spring, and means piv-

totally mounted on said frame and movable substantially vertically relative to said pin inserting means and said apertured die bed to insert a final permanent pin while the spring is so stressed.

4. In a machine for assembling pocket knives comprising a spring, permanent pins, and other parts to be assembled; the combination of a frame member, a die bed fixed to said frame member and having at least two retractable pins upon which to assemble the parts, the unstressed spring being in place, a movable jig means pivotally mounted on said die bed having apertured guides in alignment with the retractable pins, the guides being adapted to support the permanent pins in end-to-end contact with the retractable pins, pressing means pivotally mounted on said frame and movable substantially vertically relative to said jig and said die bed to insert the permanent pins into position in the knife, thereby causing the permanent pins to replace the retractable pins, means pivotally mounted on said frame and movable transversely to said jig to stress the spring, said pressing means cooperating also with another apertured guide on the movable jig means aligned with the final knife pin hole for inserting the final permanent pin while the spring is so stressed.

5. In a machine for assembling pocket knives comprising a spring, permanent pins, and other parts to be assembled; the combination of a frame member, an apertured die bed fixed to said frame member and having at least two retractable pins in said apertures upon which to assemble the parts, the unstressed spring being in place, a swinging jig means mounted on said die bed for holding said parts and spring in position, apertured guides on the jig means in alignment with the retractable pins adapted to guide the permanent pins into position in the knife, pressing means pivotally mounted on said frame and movable substantially vertically relative to said swinging jig and cooperating with the guides so as to insert the permanent pins in place of the retractable pins in the knife parts upon operation of the pressing means, means to stress the spring including an arm pivotally mounted on said frame with projections thereon adapted to move transversely to said die bed, one of said projections cooperating with the swinging jig means to hold the same in place on top of the knife parts.

6. In a machine for assembling pocket knives of different types comprising a spring, permanent pins, and other parts to be assembled; the combination of a frame, an apertured die bed fixed to said frame and having a plurality of retractable pins, certain of said retractable pins being adapted to receive said parts in assembled relation on said die bed with said unstressed spring in place, the retractable pins used being selected according to the type of knife to be assembled, a movable jig means mounted on said die bed having apertured guides in alignment with the retractable pins and adapted to support the permanent pins in end-to-end contact with the retractable pins, pressing means pivotally mounted on said frame and movable substantially vertically relative to said movable jig adapted to insert the permanent pins into position in the knife thereby causing the permanent pins to replace the retractable

pins, means pivotally mounted on said frame and movable transversely to said die bed to stress the spring, and an additional apertured guide on the movable jig means aligned with the final knife pin hole and cooperating with said pressing means for inserting the final permanent pin while the spring is so stressed.

7. In a machine for assembling pocket knives of different types comprising springs, permanent pins, and parts varying with the knife; the combination of a frame, an apertured die bed fixed to said frame and having a plurality of retractable pins in said apertures, certain of said retractable pins being adapted to receive said parts in assembled relation on said die bed with said unstressed spring in place, movable jig means mounted on said die bed having apertured guides in alignment with the retractable pins, the guide being adapted to guide the permanent pins into position in the knife, driving means pivotally mounted on said frame and movable substantially vertically relative to said guide and said die bed adapted to insert the permanent pins into position in the knife replacing the retractable pins in the knife parts, means pivotally mounted on said frame adapted to receive a tool movable transversely to said die bed for stressing the springs, the tool being shaped in accordance with the type of the knife being assembled, and an additional apertured guide on the movable jig means aligned with the final knife pin holes for inserting the final permanent pin while the spring is so stressed.

8. In a machine having a pivoted operating lever with an arcuate movement, a safety guard for covering the working end of said operating lever when the lever is approaching its operating position, said safety guard being carried on a lever pivoted between the operating lever pivot and said working end thereof, the safety guard lever having a pin cooperating with the top of the operating lever so that the safety guard is raised with the operating lever, a pin on the operating lever cooperating with a projection on the safety guard lever, the relative positions of the pivots being such that the said operating lever pin will not clear the said projection to allow the operating lever to complete its working stroke until the safety guard is in place.

9. In a machine for assembling pocket knives comprising a spring and other parts to be assembled; the combination of a frame, an apertured die bed fixed to said frame and having at least two locating pins retractable in said apertures for holding the parts and unstressed spring in place, means pivotally mounted on said die bed for inserting permanent pins in place of said locating pins, said means also holding the knife spring and parts in position, means to hold the spring and parts securely in place, said means being provided with additional means to simultaneously stress the spring, and means pivotally mounted on said frame and movable substantially vertically relative to said pin inserting means and said die bed to insert a final permanent pin while the spring is stressed.
